MODULATION SYSTEM

John J. Antalek, Chicago, Ill., assignor to The Rauland Corporation, Chicago, Ill., a corporation of Illinois

Application May 8, 1942, Serial No. 442,185

3 Claims. (Cl. 179—171.5)

This invention relates to modulation systems, especially as employed in connection with radio telegraph and telephone transmitters. More particularly it relates to a system of amplitude modulation.

One purpose of my invention is to provide a modulation system of comparatively great simplicity and one capable of modulating a carrier frequency by the use of an extremely small amount of power, the amount of power required being comparable to that required for the modulation of a transmitter of the frequency modulation type.

Another purpose of the instant invention is to provide a method of modulation adapted for use in the low frequency spectrum, due to the relatively narrow band of side frequencies produced thereby.

A further object of my invention is to provide a modulation system giving high fidelity transmission with a minimum amount of apparatus at relatively low cost and adapted to produce a transmitted signal which can be received upon apparatus of the type used for the reception of ordinary amplitude modulated signals.

My invention modulates an independently produced carrier current by varying the impedance of a circuit or circuits connected either to the grid or the anode of a tube which acts as the modulated amplifier tube. Alternatively, modulation may be secured according to my invention by varying the impedance or resonant frequency of a secondary circuit, arranged so as to withdraw energy from either the grid or the anode circuit of the modulated amplifier tube, to which it is coupled, in accordance with such changes of impedance, thus bringing about absorption modulation.

In order to explain my invention, reference is made to the accompanying drawings, where:

Fig. 1 shows one embodiment of my invention using a microphone of the variable resistance type, connected so as to secure modulation of the variable impedance type;

Fig. 2 shows another embodiment, wherein a variable inductance type of microphone is so connected as to bring about absorption modulation;

Fig. 2a shows an alternative and simple method of using a variable impedance microphone to secure impedance modulation;

Fig. 3 shows another method of securing absorption modulation by an arrangement permitting the use of any conventional source of audio-frequency modulating energy;

Fig. 4 is a graphical representation of the re-

sonance curve of typical tuned circuit with which my modulation system may be employed;

Fig. 5 shows still another method of absorption modulation according to my invention, using a series resonant circuit; and

Fig. 6 shows yet another impedance modulation method according to my invention, utilizing a series resonant circuit and an alternative method of coupling the tube producing the carrier frequency to the modulated amplifier tube.

Referring now to Fig. 1, electron tubes 1 and 2 are tetrodes and tube 3 is shown as a hexode of conventional type. Tube 1 has a piezo-electric crystal 4 connected to the grid 5 thereof and having a suitable grid leak resistor 6 shunting the crystal. The tuned anode or output circuit 7 of this tube is by-passed to ground by condenser 8 and tuned either to the fundamental frequency of crystal 4 or to some harmonic thereof, according to the design of circuit employed. The screen electrode 9 is connected through dropping resistance 10 to a source of suitable positive potential and by-passed to ground through condenser 11, while the tube cathode 12 is directly grounded.

Electron tube 2 acts as the modulated amplifier tube, having its cathode 13 grounded and its screen electrode 14 supplied with a suitable positive potential through dropping resistance 15, and bypassed to ground through condenser 16. The output circuit connected to the anode of this tube may take the form of the tuned circuit 17. The grid 18 is connected through input coil 19 and by-pass condenser 20 to the ground, while a source of suitable negative bias potential is connected to the junction point of this coil and condenser. The input circuit of tube 2 is electromagnetically coupled to the output circuit of tube 1, by means of coil 19, this coupling being quite critical.

Electron tube 3 and its associated elements constitute an electron controlled variable capacity which is effectively connected in parallel with coupling coil 19 of the input circuit of tube 2, these two elements thus constituting a circuit having a variable resonant period. In order to secure good stability and maximum efficiency, it is preferred that coil 19 have its inductance determined by so-called permeability tuning, but this is not essential. The input circuit of tube 2 is so tuned as to have, in its quiescent or non-modulated condition, a frequency which will be removed from the frequency of tuned circuit 7 by an amount corresponding approximately to that indicated at C in Fig. 4. It will be noted that point C is the middle point of the linear portion

of the selectivity or resonance curve, embraced between points A and B. This point C is usually about one percent away from the frequency of tuned circuit 7 and may be chosen upon either the plus or the minus side of the resonant point of circuit 7.

Tube 3 has its cathode 21 suitably biased through resistance 21' and by-pass condenser 22 to ground, while its two screen electrodes 23 obtain their positive potential through dropping resistor 24, 10 and are by-passed to ground through condenser 25. The control grid 26 of tube 3 is supplied with audio-frequency modulating energy through transformer 27, the primary of which is excited by microphone circuit 28.

The elements acting to give the variable capacity effect of the circuits associated with tube 3 comprise condenser 29 connected between the non-grounded end of coil 19 and anode 38, the latter of which is fed from a suitable source of 20 positive potential through choke coil 34, and variable condenser 32 and resistance 33 connected in parallel with one another and between grid 34 of the tube and the ground. Phase coupling of grid 34 to the connection between coil 19 and condenser 29 is made via series connected condenser 35 and resistance 36.

When modulation signals are impressed upon grid 26 of tube 3, the resonant frequency of the circuit comprised by coil 19 and the effective 30 capacity of tube 3 and its associated elements, is varied approximately one-half percent plus or minus the resonant frequency which this same circuit has when non-modulated. In other words, the resonant period shifts from point C as far as points A or B, thus traversing the linear portion of the resonance curve shown in Fig. 4. This results in a linear variation of the radio frequency energy applied to input grid 18 of tube 2, which tube is preferably so constructed and biased as to function as a class B amplifier, whereby the power output in anode circuit 17 will be proportional to the square of the grid excitation voltage.

While I have described and shown in Fig. 4 a selectivity curve upon which the point C is removed about one percent from resonance frequency, it is to be understood that the shape of curve and the location of point C will vary with different circuits, the elements of which have different constants or magnitudes.

In the system of modulation just described, the modulation is brought about by varying the effective impedance of the input circuit of the modulated amplifier tube, so that the amount of energy transferred thereto from the oscillator tube will vary in accordance with the modulating signals.

In the system disclosed in Fig. 2, on the other hand, modulation is brought about by varying the effective impedance of an absorption circuit coupled to the tuned input circuit of the modulated amplifier tube. In Fig. 2 the circuits associated with oscillator tube 1a are identical with those already described in connection with Fig. 1. Likewise, modulator tube 2a and its output circuit are identical with the same elements in Fig. 1, so that corresponding reference numerals are employed in connection with these two tubes. The input circuit of tube 2a comprises coil 37a and condenser 38a, connected in a resonant circuit tuned to the same frequency as circuit 1a. This tuned input circuit is conductively coupled by conductor 39a, enclosed in grounded conductor 40a so as to form a flexible low impedance trans-

mission line, to a microphone 41a of the variable inductance type, suitably shielded as indicated at 42a. This microphone includes an inductance 43a, varied by means of a suitable diaphragm connected thereto, and a variable condenser 44a, connected in parallel with the inductance. The tuned circuit thus formed is conductively coupled through conductor 39a, already referred to, to the input circuit of tube 2a, and is tuned to a frequency corresponding to the point C of Fig. 4, for the reasons already explained in connection with Fig. 1. When 44a is varied in inductance by the sound input to 41a, the energy absorbed from input circuit 37a, 38a will be varied correspondingly, thus causing absorption modulation of the input energy to tube 2a.

Referring now to Fig. 2a, there is here shown one comparatively simple form which my invention may assume. In this form the modulating device is physically, as well as electrically, incorporated into the circuits coupling the oscillator to the modulated amplifier. The variable inductance microphone of Fig. 2 may be used to secure impedance modulation, instead of absorption modulation, by connecting the microphone directly in place of the circuit constituted in Fig. 2 by coil 37a and condenser 38a. The system will then function similarly to that of Fig. 1.

With the system of Figs. 2 and 2a, a condenser type of microphone may be employed in lieu of the variable impedance type, sound impingement upon the microphone causing the same shift of resonant period as in the case of the use of a variable impedance type microphone.

In the system shown in Fig. 3, the circuits of tubes 1b and 2b are similar to those shown in Fig. 2, except that as an alternative method, a separate output circuit 46b is shown coupled to the tuned anode circuit 17b, of tube 2b. Modulation is secured by inductively coupling coil 46b to coil 37b and tuning the former coil by connecting it effectively in shunt with the variable capacity presented by tube 3b and its associated elements, these latter being connected in the same manner indicated in Fig. 1. The resonant circuit formed by coil 46b and tube 3b is tuned to a point corresponding to C of Fig. 4, as previously described, and the variation of the effective capacity of tube 3b by the modulating energy supplied to input grid 26b, thereof, causes a varying absorption of energy by coil 46b from the input circuit of tube 2b, thus modulating the radio-frequency energy supplied to grid 18b thereof.

In Fig. 5 oscillator tube 1c and modulator tube 2c are connected in a fashion similar to that shown in Fig. 3. Likewise tube 3c functions in the same manner as in Figs. 1 and 3. The transfer of energy between tube 3c and the input circuit of tube 2c is by a connection to the midpoint 47c of series resonant circuit 48c, 49c, this latter circuit as a whole being connected in parallel with the input circuit of tube 2c and tuned to point C of Fig. 4. This series circuit absorbs energy in accordance with the variation of its effective impedance by the modulator of tube 3c.

In Fig. 6 oscillator tube 1d has its tuned output circuit 50d by-passed to ground at 51d, fed through coupling condenser 52d and conductively coupled to input grid 18d of modulator tube 2d, through coil 48d. Anode supply is through choke coil 53d. Coil 48d and condenser 49d form a series resonant circuit conductively coupled to tuned output circuit 53d of tube 1d. Tube 3d and its associated elements are connected and act in the same fashion as indicated in Figs. 1, 3

and 5. The effective capacity of tube 3d is modulated by the signals impressed upon control grid 26d and this capacity is connected to the point of common connection 47d, between coil 48d and condenser 49d. In operation, modulation of tube 3d results in corresponding variation of the impedance of circuit 48d, 49d, which is tuned to a point corresponding to C of Fig. 4, as previously described. This causes the radio frequency energy supplied to grid 18d to be modulated in accordance with the modulating energy supplied to transformer 27d.

It is preferred that my modulation systems be connected to the radio-frequency tuned circuits carrying low power in a transmitter, for the reason that it is then much easier to modulate the lower energy level there present. However, my systems are applicable for tuned circuits carrying any amount of energy. For example the modulator tube 3 may be coupled to the anode circuit of tube 2, instead of being coupled to the input circuit.

The selectivity of the circuits involved, the circuit constants, and the proper adjustment of all the resonant circuits are some of the factors which determine the percentage of modulation to be attained by the employment of my invention.

While the resonant circuit including 18 (Fig. 1) and the corresponding resonant circuits of the other figures are preferably tuned to a frequency which is of the order of one or one-half percent removed from the carrier frequency, the difference may be higher. For instance, with a carrier frequency of 1000 k. c. the resonant circuit could be tuned to 1080 k. c. or 920 k. c., i. e., 8% removed. This depends on the coefficient of the coupling and the efficiency of the resonant circuits, e. g., 7 and 19 in Fig. 1, and on the result desired.

In Figs. 1, 3 and 5 the resonant circuits, e. g., 19 in Fig. 1, could be tuned to the exact carrier frequency and tube 3 used as a loading device to vary the impedance of the circuit thereby obtaining radio frequency modulation of the grid 18. In Fig. 3 the corresponding resonant circuit is the one including 48b and in Fig. 5 it is 48c.

An important advantage of my system of modulation is that it makes possible a greater percentage of modulation without distortion than would be possible with conventional types of amplitude modulation systems. This can be done by biasing tube 3 to a suitable value on its grid voltage plate current characteristic curve so that during the modulation cycle the negative modulation peaks will be limited to a value never to exceed a point where the carrier would be cut-off.

The positive peaks may reach a value which is three or four times the value of the carrier without modulation. Thus a controlled carrier system is produced.

What I claim is:

1. A high level modulation system including a source of carrier frequency energy, a modulated amplifier excited by said energy, primary tuned circuit means coupling said source and said modulated amplifier and tuned to said carrier frequency, and a secondary resonant circuit discrete from but coupled directly to said primary coupling means and tuned to a frequency slightly different from said carrier frequency, so that said secondary circuit quiescently absorbs only a portion of the energy of said carrier frequency, said secondary circuit including means for varying the resonant period thereof at audio-frequency, whereby said secondary circuit absorbs energy from said primary circuit in accordance with the audio-frequency variations of resonant period and thereby modulates the carrier frequency energy in said primary circuit, but at the same time said resonant period is kept at all times different from said carrier frequency.

2. A high level modulation system including an oscillator providing energy and a modulated amplifier coupled by at least one tuned circuit resonant to the frequency of said oscillator, and an audio-frequency modulating element of the variable impedance type including a second tuned circuit physically discrete from said tuned coupling circuit, but conductively coupled thereto and quiescently resonant to a frequency departing by about one per cent from the frequency of said oscillator, whereby alteration of the quiescent state of said modulating element will alter the resonant period of said second tuned circuit so as to absorb varying amounts of oscillator energy from said first mentioned tuned circuit and thereby will modulate said oscillator energy.

3. The method of modulating at high level a first circuit carrying energy of a predetermined radio frequency with a second circuit coupled to said first circuit, which includes the steps of tuning said second circuit to a quiescent frequency slightly different from said predetermined radio frequency and varying the tuning of said second circuit at the modulation frequency, but keeping the tuning thereof at all times different from said predetermined radio frequency, whereby a carrier wave determined by said radio frequency is never wholly suppressed and whereby said second tuned circuit acts to variably absorb energy from said first circuit at said modulation frequency.

JOHN J. ANTALEK.
